[57] CLAIM

The ornamental design for a eyeglasses holder, as shown.

DESCRIPTION

FIG. 1 is a front elevation view.

FIG. 2 is a side elevation view; and,

FIG. 3 is a front elevation view shown without broken lines.
The surface(s) or portion(s) of the article not shown in the
drawing or described in the specification form(s) no part of
the claimed design.

The broken lines showing of environment in the drawings is
for illustrative purposes only and forms no part of the
claimed design.

Two dome shaped apertures appear on the front plate of the
holder. The screw/bolt heads which appear on the rear plate
of the holder are shown through the apertures.
